TELEMETERING SYSTEM

Lan J. Wong, Cincinnati, Ohio

Application July 19, 1954, Serial No. 444,235

14 Claims. (Cl. 340—359)

This invention relates to digital telemetering systems for transmitting in the form of coded electrical pulses the numerical values of one or more conditions which may vary with time. Objects and advantages of the invention will appear as the description proceeds.

In a preferred embodiment of the invention, a telemeter transmitter has a plurality of code drums, positioned side by side, rotatable about a common axis. Each drum has an electrically non-conductive peripheral surface with a plurality of conductive contact strips, of wide and narrow widths respectively, axially spaced apart thereon and each extending circumferentially part-way around the drum. An oscillatory contact arm moves axially across the peripheral surfaces of the drums successively, and as the contact arm crosses each contact strip an electrical pulse is produced. A wide contact strip produces a relatively long pulse, and a narrow contact strip produces a shorter pulse. Each drum has one wide contact strip and four narrower contact strips so arranged on the peripheral surface that each of ten substantially equal sectors of the drum is different from any other such sector of the same drum with respect to the number of wide and narrow contact strips thereon. Consequently, as the contact arm crosses each drum, any one of ten different combinations of long and short pulses may be produced, depending upon the angular position of the drum. These pulses may represent numbers in accordance with the following code:

Long pulses	Short pulses	Numerical value
0	0	0
0	1	1
0	2	2
0	3	3
0	4	4
1	0	5
1	1	6
1	2	7
1	3	8
1	4	9

In the alternative embodiment, all of the contact strips on each code drum are substantially the same width, and a series of zero to nine pulses of substantially equal length represent the digits zero to nine, respectively.

Means are provided for rotating the drums in accordance with changes in value of the varying condition. Each drum is connected to the next adjacent drum through intermittent gearing such that as one drum completes a full revolution the next drum is rotated by one-tenth revolution. Thus three drums are sufficient to produce coded electrical pulses respectively representing one thousand different numerical values of the varying condition. The telemeter receiver preferably includes an electrical chart recorder for displaying a record of the pulses on a strip of chart paper; but it should be understood that other types of receiver may also be used, such

2

as a receiver having means for printing the respective digits represented by each series of pulses.

Either before or after crossing the code drums, preferably before, the oscillating contact arm crosses a series of fixed contacts and thereby produces a coded series of pulses which identifies the transmitter. Several transmitters may be used in the same telemetering system to transmit selectively the numerical values of several different varying conditions. The several transmitters may be similar except that each has its own distinctive arrangement of fixed contacts which produce, each time that transmitter is operated, a distinctively coded series of pulses which identifies the transmitter in the permanent record displayed on the receiver chart. If desired, the receiver may also be provided with a conventional time-stamp mechanism for printing on the chart the time when each recording is made, so that the receiver chart contains a permanent record of the transmitter identification, the numerical values transmitted, and the time.

The invention will be better understood from the following description taken in connection with the accompanying drawings, and its scope will be pointed out in the appended claims. In the drawings,

Fig. 1 is a schematic plan view showing an illustrative embodiment of my telemetering system, with inner and outer cover plates removed from the transmitter drum box,

Fig. 2 is a plan view of the transmitter drum box with the inner cover plate in place,

Fig. 3 is a plan view of the transmitter drum box with the outer cover plate in place,

Fig. 4 is a section view taken generally along the line 4—4 of Fig. 1, with both inner and outer cover plates in place,

Fig. 5 is a developed view of the peripheral surface of a code drum, showing a preferred arrangement of the contact strips, and

Fig. 6 is a developed view of the peripheral surface of a code drum, showing an alternative arrangement of the contact strips.

Fig. 7 is a cross-sectional view of cover-plate 51 taken on the line 7—7 of Fig. 3.

Referring now to Figs. 1 through 5, inclusive, the drawings illustrate a telemetering system used to indicate liquid level—for example, the water level in a river. A float 1, which rides on the surface of the water, is connected to one end of a cable 2 which encircles a drum 3. The cable is kept taut by suitable means such as a weight 4 attached to its other end. Drum 3 is connected through shaft 5, gear 6 and gear 7 to the input shaft 8 of the telemeter transmitter. Float 1 rises and falls with changes in the water level, and through the linkage shown rotates shaft 8. Thus shaft 8 is rotated in accordance with changes in the water level of the river. It will be appreciated that other means may be employed to rotate shaft 8 in accordance with changes in the value of any varying condition which it is desired to transmit, such as the amount of rainfall collected in a suitable vessel, the weight of material placed on a scale, or any other measurable value.

The transmitter is mounted on a base plate 9, which in practice may be attached to, or a part of, a case (not shown) enclosing and protecting the transmitter. The input shaft 8 extends through the transmitter drum box 10, as shown, and is connected through gears 11 and 12 to a conventional three-digit mechanical revolution counter 13. Counter 13 responds to the rotation of shaft 8, and indicates the water level of the river in tenths of a foot between 0 and 99.9 feet. As is hereinafter described, the transmitter also operates to produce coded electrical

pulses which correspond to the three digits displayed by counter 13.

Shaft 8 is connected through gears 14 and 15 to a first code drum 16. Drum 16 is connected through intermittent gearing 17 to a second code drum 18. The gearing 17 may be a set of Geneva gears or the like, such as are commonly used in mechanical counting devices, to rotate drum 18 one-tenth revolution as drum 16 completes each full revolution. Drum 18 is similarly connected through intermittent gearing 19 to a third code drum 20, so that drum 20 is rotated one-tenth revolution as drum 18 completes each full revolution. Thus drums 16, 18 and 20 are rotated to angular positions which correspond respectively to the right, center and left digits displayed by counter 13.

Fig. 5 is a developed view showing the peripheral surface of drum 16. The surfaces of drums 16, 18 and 20 preferably are identical. Axially spaced apart on the peripheral surface of the drum are a relatively wide contact strip 21 and four narrow contact strips 22, 23, 24 and 25. Preferably, the wide contact strip is about three times as wide as a narrow contact strip. Each of the narrow strips is divided into two circumferentially spaced-apart sections, the second section of strips 22, 23, 24 and 25 being shown at 22', 23', 24', and 25' respectively.

In a preferred construction of the code drums, the contact strips are the exposed rims of metal washers embedded in a phenolic plastic which forms the body of the drum and provides an electrically non-conductive peripheral surface except where the metal washers are exposed. A part of the rim of each washer is cut away and the space thus left is filled with non-conductive plastic to form the contact strip arrangement shown in the drawings. All of the contact strips are electrically conductive, and are electrically grounded to base plate 9 through drum box 10 and a metal shaft 26 upon which drums 16, 18 and 20 are rotatably mounted. The contact strips may be chrome flashed to resist corrosion and wear.

Referring especially to Fig. 5, it will be noted that each of ten substantially equal sectors of drum 16 differs from every other such sector with respect to the number of wide and narrow contact strips on its surface. Starting at the bottom of Fig. 5, the first sector 27, representing the digit 0, contains no contact strip; the second sector 28, representing the digit 1, contains one narrow contact strip; the third sector 29, representing the digit 2, contains two narrow contact strips; the fourth sector 30, representing the digit 3, contains three narrow contact strips; the fifth sector 31, representing the digit 4, contains four narrow contact strips; the sixth sector 32, representing the digit 5, contains one wide contact strip; the seventh sector 33, representing the digit 6, contains one wide and one narrow contact strips; the eighth sector 34, representing the digit 7, contains one wide and two narrow contact strips; the ninth sector 35, representing the digit 8, contains one wide and three narrow contact strips; and the tenth sector 36, representing the digit 9, contains one wide and four narrow contact strips. Each sector contains the same number of narrow contact strips as the diametrically opposite sector, but only the last five sectors contain the wide contact strip.

Referring especially to Figs. 1 and 4, an oscillatory contact arm has a non-conductive part 37, preferably made of phenolic plastic, and a conductive part 38, preferably made of a metal such as Phosphor bronze, fastened together by suitable means such as rivets 39. Two electrical contact points 40 and 41, preferably made of platinum alloy to resist tarnish and corrosion, are attached to the tip of part 38 on its top and bottom, respectively. One end of the contact arm is pivoted on a post 42 so that the other end of the contact arm, which carries points 40 and 41, can move back and forth in the axial direction of code drums 16, 18 and 20.

In operation of the transmitter, the contact arm is

oscillated by means hereinafter described in such a way that contact 41 is raised away from engagement with the code drums as the contact arm moves from right to left, and is lowered to touch the peripheral surfaces of the drums as the contact arm moves from left to right. Thus, during each oscillatory cycle of the contact arm, point 41 moves in a substantially axial direction from left to right across the tops of code drums 20, 18 and 16, successively. During such movement, point 41 touches and crosses a number of the contact strips which depends upon the respective angular positions of the code drums, and hence depends upon the numerical value of the water level or other variable condition to be transmitted.

Whenever point 41 of the contact arm touches the electrically grounded contact strips, an electrical circuit is completed from electrical power supply 43 through the winding of a relay 44, current-limiting resistor 45, contact arm parts 38 and 41, and the contact strips. Current flows in this circuit while point 41 crosses the contact strip, and forms an electrical pulse of a length which depends upon the velocity of point 41 and the width of the contact strip being crossed. The wide contact strips produce relatively long pulses, and the narrow contact strips produce short pulses. Each such pulse operates relay 44 to close relay contacts 46 and produce a similar but amplified pulse in the telemetering signal channel represented by wires 47 and 48.

The chief purpose of relay 44 is to amplify the pulses. Where weak signals are permissible in the telemetering channel, relay 44 may be omitted and the contact arm connected directly to the signal channel. It will also be appreciated that the telemetering signal channel may include, in place of or in addition to wires 47 and 48, a radio link or any other means for transmitting electrical pulses.

To keep the tip of the contact arm from dropping into the spaces between the code drums, the drum box is provided with an inner cover plate 49, as shown in Figs. 2 and 4. This inner cover plate is made of electrically non-conductive material, such as phenolic resin or other plastic, and is fastened in place by suitable means such as screws 50. Plate 49 covers the gears in the drum box and includes a plurality of tongues 49' which extend between and on each side of the code drums, as shown. The tops of tongues 49' are level with the tops of the code drums, so that a substantially smooth non-conductive surface is provided for contact point 41 to ride upon as it moves from one code drum to another.

An outer cover plate 51, shown in Figs. 3 and 4, is fastened to the top of the drum box by screws 52. Plate 51, preferably made of phenolic plastic, has a flat non-conductive bottom surface which contact point 40 slides across as the contact arm moves from right to left during its oscillatory cycle. Eight holes, which extend through plate 51 along a line substantially parallel to the axis of the code drums, are threaded to receive metal screws 53 and plastic screws 54. The lower ends of screws 53 and 54, which are substantially flush with the bottom of plate 51, are crossed by contact point 40 as it moves from right to left across the bottom of the outer cover plate. The heads of screws 53 are in electrical contact with a metal plate 55, which is fastened between the screw heads and plate 51, as shown. Plate 55 is electrically grounded to base plate 9 through lead 55', screw 52' and drum box 10.

The electrically grounded metal screws 53 serve as fixed contacts for transmitter identification purposes. Each time that contact 40 crosses a screw 53 an electrical pulse is produced in the same manner as occurs when contact 41 crosses a contact strip of the code drums. When several transmitters are used in the same telemetering system, different numbers or arrangements of metal screws 53 are used in the different transmitters, so that each transmitter produces its own distinctively coded

series of identification pulses which differs from that of the other transmitters. Plastic screws 54, which are non-conductive, fill the unused holes in plate 51 to maintain a substantially flat surface for contact point 40 to slide across. The identification code of any transmitter can be changed quickly and easily, whenever desired, by removing screws 53 and 54 and replacing them in different proportions or sequences in the eight holes provided.

The means for oscillating the contact arm includes an electric motor 56 mounted beneath a motor bracket 57. Through conventional speed-reducing gearing inside the motor housing, motor 56 rotates a cam shaft 58 and cam 59 in a clockwise direction. A pin 60, attached to cam 59 parallel with and eccentric to shaft 58, engages a lengthwise slot 61 in the contact arm and oscillates the contact arm about its pivot at 42 through an arc of about twenty degrees. This oscillation moves the contact arm tip carrying contact points 40 and 41 back and forth substantially parallel to the axis of the code drums in the space between the tops of the code drums and the bottom of plate 51.

During the time that pin 60 is moving the contact arm from right to left, cam 59 engages a hinged flap 62 which in turn engages the bottom part 37 of the contact arm and raises the arm so that contact 41 is lifted away from engagement with the code drums and contact 40 is brought into engagement with the bottom of plate 51 and crosses the fixed contact screws 53 to produce the coded series of transmitter identification pulses. During the remainder of the oscillatory cycle, when the contact arm moves from left to right, cam 59 permits flap 62 and the contact arm to drop sufficiently so that contact point 40 drops out of engagement with plate 51 and contact point 41 is brought into engagement with and successively crosses the code drums 20, 18 and 16 to produce the coded series of pulses which represent the numerical value to be transmitted. A stop 63 limits the downward motion of the hinged flap 62 so that it remains in a favorable position to re-engage cam 59 at the beginning of the next cycle.

Since the cam shaft and cam rotate in the clockwise direction as viewed in Fig. 1, pin 60 is nearer pivot 42 during right-to-left motion of the contact arm than it is during left-to-right motion. Consequently, the right-to-left motion is somewhat faster, and is completed in slightly less than one-half of the oscillatory cycle. This leaves more time for the contact arm to move across the code drums, and thus provides better resolution of the pulses representing numerical values without increasing the total cycle time. Because of the relatively rapid motion of the contact arm across screws 53, the transmitter identification pulses are relatively short despite the substantial width of the screws.

On the other hand, variations in velocity of the contact arm as it crosses the code drums causes some variation in the length of pulses produced as different contact strips are crossed. However, using wide contact strips about three times the width of the narrower contact strips, I have experienced no difficulty in distinguishing the long pulses from the short pulses. If required, the variations in pulse length due to contact arm velocity changes can be minimized or eliminated by compensating variations in the widths of the contact strips, making the strips narrower where the contact arm velocity is lowest and wider where the velocity is greatest. For manufacturing and maintenance convenience, however, I prefer to avoid such compensations and to make all of the code drums identical.

Between oscillatory cycles, the contact arm stops at a rest position, illustrated in Fig. 1, at the right end of its oscillatory path. In this rest position, the contact arm engages a switch lever 64 which opens a normally-closed switch 65.

To operate the transmitter and initiate an oscillatory

cycle of the contact arm, a normally-open starting switch 66 is held closed for a few moments, to complete a circuit from power supply 43 to a starting relay 67. This closes the relay contacts 68 and supplies electric power through leads 69 and 70 to start motor 56. As the motor starts it rotates cam 59 and moves the contact arm to the left away from its rest position. Switch 65 now closes, and since it is connected in parallel with relay contacts 68, it continues to supply electric power to operate motor 56, even though switch 66 may now be released and reopen. The motor continues to operate until an oscillatory cycle has been completed and the contact arm returns to the rest position. The contact arm then engages level 64 to open switch 65, and the motor stops until switch 66 is closed again.

As the contact arm successively crosses the fixed contacts 53 and the code drums 20, 18 and 16, electrical pulses are produced as hereinbefore explained and the pulses are transmitted over the telemetering signal channel comprising wires 47 and 48. These pulses are received by receiver apparatus including an electrical chart recorder 71 which displays the pulses on a strip of chart paper 72. The first coded series of pulses received, displayed at 73, identifies the transmitter. The next three series of pulses, displayed at 74, 75 and 76, respectively, represent the numerical value transmitted, which in the case illustrated is the number 791.

Another transmitter 77, responsive to numerical values of another varying condition and having its identification code screws differently arranged, but otherwise identical to the transmitter hereinbefore described, may be connected to the same telemetering signal channel. Transmitter 77 is operated by closing its starting switch 78, whereupon it transmits pulses which are displayed by receiver 71. The series of identification pulses, which is different for each transmitter, permanently identifies on the receiver chart the transmitter, and hence the varying condition, to which the numerical values which follow are related. Because of this feature, many transmitters may be connected to the same telemetering channel without risk of confusing the recorded data.

Fig. 6 is a developed view showing the peripheral surface of an alternative code drum 16' which may be used in place of the code drum 16. Alternative drums 18' and 20', similar to drum 16' and therefore not illustrated, may be used in place of drums 18 and 20, respectively. Axially spaced apart on the peripheral surface of drum 16' are nine contact strips, 79 through 87, inclusive, all substantially equal in width but different in length. These contact strips are so arranged on the drum surface that each of ten substantially equal sectors of drum 16' differs from every other such sector with respect to the number of contact strips on its peripheral surface. The ten drum sectors contain 0, 1, 2, 3, 4, 5, 6, 7, 8 and 9 contact strips, respectively, which produce a corresponding number of electrical pulses of substantially uniform length when the oscillatory contact arm moves across a sector of drum 16'. With this arrangement, the number of pulses in each series is the same as the digit represented thereby. Except for the different contact strip arrangement, drum 16' is preferably identical to drum 16, although it may be made somewhat wider to accommodate the larger number of contact strips more easily.

My invention is not limited to the specific embodiments herein illustrated and described. It is intended that the following claims should cover all changes and modifications which do not depart from the true spirit and scope of the invention.

I claim:

1. A telemeter transmitter comprising at least one rotatable drum having an electrically non-conductive peripheral surface, a plurality of conductive contact strips axially spaced apart on said peripheral surface and each extending circumferentially part-way around said drum, a fixed plate having a non-conductive surface facing said

drum, a plurality of fixed conductive contacts spaced apart on said surface of said plate along a line substantially parallel to the axis of said drum, an oscillatory contact arm movable substantially parallel to said drum axis between said plate and said drum, means to move said arm parallel to said drum axis back and forth in oscillatory cycles, means moving said arm into contact with said plate as said arm moves in one direction of its oscillatory motion and into contact with said drum as said arm moves in the opposite direction, and means producing an electrical pulse each time said contact arm touches any of said fixed contacts and said contact strips.

2. A telemeter transmitter comprising at least one rotatable drum having an electrically non-conductive peripheral surface, a plurality of conductive contact strips axially spaced apart on said peripheral surface and each extending circumferentially part-way around said drum, a fixed plate having an electrically non-conductive bottom surface positioned above and spaced apart from said drum, said plate having a plurality of threaded holes therethrough along a line substantially parallel to the axis of said drum, a plurality of removable screws within said holes extending downward to the bottom surface of said plate, selected ones of said screws being electrically conductive and forming a coded series of fixed contacts, the remaining ones of said screws being non-conductive, an oscillatory contact arm pivoted at one of its ends, the other end of said arm being movable substantially parallel to said drum axis between said plate and said drum, said arm having a lengthwise slot, a cam and cam shaft, a motor operable to rotate said cam and cam shaft, a pin mounted on said cam parallel with and eccentric to said cam shaft, said pin engaging said slot to move said contact arm back and forth in oscillatory cycles as said cam shaft rotates, a hinged flap engaging said cam during substantially one-half of each revolution of said cam shaft, said cam during such engagement moving said hinged flap upward into engagement with said arm and thereby lifting said arm away from contact with said drum into contact with said plate, whereby said arm touches the peripheral surface of said drum as it moves across the drum in one direction and touches said plate as it moves across in the other direction, and means producing an electrical pulse each time said contact arm touches any of said fixed contacts and said contact strips.

3. A telemetering system for transmitting numerical values of a varying condition, comprising at least one rotatable drum having an electrically non-conductive peripheral surface, a plurality of conductive contact strips axially spaced apart on said peripheral surface and each extending circumferentially part-way around said drum, said strips being of wide and narrow widths respectively and being so arranged that each of ten substantially equal sectors of said drum is different from any other such sector with respect to the number of wide and narrow contact strips thereon, means rotating said drum selectively to a plurality of angular positions corresponding to respective numerical values of the varying condition, a fixed plate having a non-conductive surface facing said drum, a plurality of fixed conductive contacts spaced apart on said surface of said plate along a line substantially parallel to said drum axis, an oscillatory contact arm movable substantially parallel to said drum axis between said plate and said drum, means including an electric motor operable to move said arm back and forth in oscillatory cycles, means moving said arm into contact with said plate as said arm moves in one direction and into contact with said drum as said arm moves in the other direction, said arm having a rest position at one end of its oscillation path, electrical circuit means for starting said motor to initiate an oscillatory cycle of said arm, means including a normally-closed electric switch for operating said motor to complete the oscillatory cycle of said arm, means engaging said arm and opening said switch when said arm

returns to its rest position, means producing long and short electrical pulses as said contact arm touches and crosses said wide and narrow contact strips respectively and producing other electrical pulses as said contact arm touches and crosses said fixed contacts, and a receiver which records said pulses.

4. A telemeter transmitter comprising a frame, at least one coding drum mounted for rotation within said frame, means for rotating said drum selectively to a plurality of angular positions in accordance with a varying condition, an arm pivotally supported at one end upon said frame, electrical contact means on the other end of said arm, means operable to oscillate said arm about its pivotal support to traverse said other end of said arm from a rest position back and forth across the peripheral surface of said drum in a direction substantially parallel to the axis of rotation of said drum, electrical contact means upon the peripheral surface of said drum for indicating the angular position of said drum with respect to said frame, electrical contact means fixedly mounted upon said frame in alignment with the path of movement of said arm, and means cooperative with said oscillating means for engaging said contact means on said arm with said contact means on said drum during movement of said arm in one direction across said drum and for engaging said contact means on said arm with said contact means on said frame during movement of said arm in the other direction across said drum.

5. A telemeter transmitter as recited in claim 5 wherein the means for oscillating the arm comprises a constant speed motor, a pin eccentrically secured to the motor shaft and engaging a slot in said contact arm whereby said arm is moved across said contact means on said frame at a velocity greater than the velocity at which said arm is moved across the peripheral surface of said drum.

6. A telemeter transmitter as recited in claim 5 wherein said electrical contact means on said drum comprises a plurality of axially spaced contact strips embedded in said drum, each of said strips being of different circumferential extent to define a plurality of sectors on the peripheral surface of said drum, each of said sectors being different from any other sector with respect to the number of contact strips thereon.

7. A telemeter transmitter as recited in claim 7 wherein the means for oscillating the arm comprises a constant speed motor, a pin eccentrically secured to the motor shaft and engaging a slot in said contact arm whereby said arm is moved across said contact means on said frame at a velocity greater than the velocity at which said arm is moved across the peripheral surface of said drum.

8. A telemeter transmitter as recited in claim 8 wherein each of said contact strips comprises an exposed portion of the rim of a metal washer, the exposed portion of said washer having a diameter equal to the diameter of said drum.

9. A telemeter transmitter comprising a frame, a plurality of coding drums mounted for rotation about a common axis within said frame, means for rotating said drums selectively to a plurality of angular positions in accordance with a varying condition, an arm pivotally supported at one end upon said frame, electrical contact means on the other end of said arm, means operable to oscillate said arm about its pivotal support to traverse said other end of said arm from a rest position back and forth across the peripheral surfaces of said drums in a direction substantially parallel to said common axis, electrical contact means upon each of said drums for indicating the angular position of said drums with respect to said frame, electrical contact means upon said frame, and means cooperative with said oscillating means for engaging said contact means upon said arm with the contact means on said drums during movement of said arm in one direction across said drums and for engaging said contact means on said arm with said contact means on said frame during movement of said arm in the other direction.

10. A telemeter transmitter as recited in claim 9 wherein the means for oscillating the arm comprises a constant speed motor, a pin eccentrically secured to the motor shaft and engaging a slot in said contact arm whereby said arm is moved across said contact means on said frame at a velocity greater than the velocity at which said arm is moved across the peripheral surfaces of said drums.

11. A telemeter transmitter as recited in claim 9 wherein in said drums are axially spaced from each other and means are provided in the space between respective drums to maintain said arm in alignment with the peripheral surfaces of adjacent drums during movement of said arm from the peripheral surface of one drum to the peripheral surface of an adjacent drum.

12. A telemeter transmitter as recited in claim 11 wherein the means for oscillating the arm comprises a constant speed motor, a pin eccentrically secured to the motor shaft and engaging a slot in said contact arm whereby said arm is moved across said contact means on said frame at a velocity greater than the velocity at which said arm is moved across the peripheral surfaces of said drums.

13. A telemeter transmitter comprising a plurality of axially spaced electrically conductive washers, each of said washers having a portion of its circumferential surface in the shape of a circular arc, said washers being embedded in a body of electrically non-conductive material with the aforementioned circumferential surface portions of said washers cooperating with the peripheral surface of said body to define a smooth cylindrical surface, means

5

10

15

for connecting said washers into a first part of an electrical circuit, and contact means connected to a second part of said electrical circuit and movable into engagement with the peripheral surface of said body and the circumferential surface portions of said washers to selectively connect and disconnect the first and second parts of said electrical circuit.

14. A telemeter transmitter as recited in claim 13 wherein the length of the circumferential surface portion of each of said washers is different than the length of the circumferential surface portion of other washers whereby the peripheral surface of said cylindrical body is divided into a plurality of sectors, each of said sectors being different from any other sector with respect to the number of surface portions of said washers therein.
